United States Patent Office

Des. 198,432
Patented June 16, 1964

198,432

BATH BRUSH OR THE LIKE

Joseph Vallis, 353 Cortleigh Blvd., Toronto,
Ontario, Canada

Filed Feb. 23, 1962, Ser. No. 68,929

Term of patent 14 years

(Cl. D9—2)

Fig. 1.

Fig. 4.

Fig. 2.

Fig. 3.

FIG. 1 is a front elevational view of the bath brush or the like showing my new design;

FIG. 2 is a top plan view thereof;

FIG. 3 is a bottom plan view thereof; and

FIG. 4 is a side view thereof.

The rear of the handle, not shown, is flat and plain.

The dominant features of my design reside in the portions shown in full lines.

I claim:

The ornamental design for a bath brush or the like, as shown and described.
